UNITED STATES PATENT OFFICE.

BARTLETT M. WORTHINGTON, OF MADISON, WISCONSIN.

DESIGN FOR PENS.

Specification forming part of Design No. **7,205**, dated February 24, 1874; application filed January 22, 1874.
[Term of Patent 14 years]

To all whom it may concern:

Be it known that I, BARTLETT M. WORTHINGTON, of Madison, in the county of Dane and State of Wisconsin, have invented a new and Improved Design for Pens, of which the following is a specification:

The invention relates to a new configuration of pen, whereby a more graceful aspect (while the pen-stock is held in the hand of the writer) is presented, and a more pleasing effect produced upon the mind of the beholder.

The drawing is a plan view of the pen.

a represents the shank of a semi-oval pen; *b*, a set-off at one side, and *c* a straight nib oblique in direction.

It will be perceived that, instead of forming the part *b* (that allows the nib to be set ob-

liquely to the shank *a*) as simply a bend of the shank, I make it in appearance separate and independent, the lines *d e f* of demarkation being distinct and well defined. When placed in its stock, and held in the hand of the writer, its curved outline and very apparent lines of demarkation cause it to present a very graceful appearance.

What I claim as my invention is—

The combination of straight shank *a*, curved set-off *b*, and parallel-edged nib *c*, provided with lines of demarkation *d e f*, to form a new design for pens.

BARTLETT M. WORTHINGTON.
